UNITED STATES PATENT OFFICE

126,866

DESIGN FOR A BEDPAN CUSHION

Elsie E. Miller, Iowa Falls, Iowa

Application June 6, 1940, Serial No. 92,860

Term of patent 14 years

To all whom it may concern:

Be it known that I, Elsie E. Miller, a citizen of the United States, residing at Iowa Falls, in the county of Hardin and State of Iowa, have invented a new, original, and ornamental Design for a Bedpan Cushion, of which the following is a specification, reference being had to the accompanying drawing, forming part thereof.

I claim:

The ornamental design for a bedpan cushion, as shown.

ELSIE E. MILLER.
